J. B. ALEXANDER'S improvement in
device for adjusting LAMP WICKS.

United States Patent Office.

JOSEPH BELL ALEXANDER, OF WASHINGTON, DISTRICT OF COLUMBIA.

Letters Patent No. 71,566, dated December 3, 1867.

IMPROVEMENT IN LAMPS.

The Schedule referred to in these Letters Patent and making part of the same.

TO ALL WHOM IT MAY CONCERN:

Be it known that I, JOSEPH BELL ALEXANDER, of Washington, in the county of Washington, in the District of Columbia, have invented a new and improved Device for Adjusting the Wicks of Lamps; and I do hereby declare that the following is a full, clear, and exact description thereof, reference being had to the accompanying drawings, and to the letters of reference marked thereon, making a part of this specification.

Figure 1 represents in perspective a view of the single plate wick-holder, with its turned edges C and C', and its turned lip or stop D.

Figure 2 represents in perspective a view of the wick-holder containing two pieces of wick, and showing at N the manner in which a new wick may be added to one that is becoming too short to reach the oil in the fountain of the lamp.

Figure 3 represents in perspective a view of the wick-tube, with notches E and E' into its edges, instead of the slots in the wick-tubes in common use.

Figure 4 represents in perspective a view of the wick-holder A, charged with a wick, W, and inserted in the wick-tube B, so that its edges may be acted on by the bevelled friction-collars G and G', through the notches E and E', for the purpose of raising or lowering the wick.

Figure 5 represents a transverse sectional view of a burner in the plane of the axle F, showing the manner in which the bevelled friction-collars G and G', pressed by the spring S and S', bind with a wedge-like grip upon the free edges of the wick-holder A.

Figure 6 represents a vertical sectional view of a burner, with the wick-holder plate A, without a wick, inserted into the wick-tube B, and pushed up until it rises above the mouth or slot in the cone L, showing the manner in which the stop D arrests its further progress upward.

Similar letters of reference denote like parts where they occur in the several figures.

The nature of my invention consists in an improvement upon a patent (No. 64,056) granted to me, April 23, 1867, for a device for raising and lowering lamp-wicks through the wick-tube, with certainty, facility, and perfectness, wherein I claimed the use of two metal plates, with turned edges to fit the one into the other, as a wick-holder, and moved in the wick-tube by milled friction-collars acting through slots on both its sides. In my present improvement I use but one plate, with turned edges, as a wick-holder, and move it in the wick-tube by means of bevelled friction-collars attached to but one axle, and acting from one side; and by a wedge-like grip upon the wick-holder plate when its edges, exposed through notches in the edges of the wick-tube, are pressed between the bevelled inside faces of the friction-collars, thus forming an entirely new device, easier to manufacture, more simple in its arrangement, and more certain and lasting in its action.

To enable others skilled in the art to make and use my invention, I will proceed to describe its construction and operation.

I make a wick-tube, of brass or other metal, like those in common use, with the exception, that instead of cutting slots in the side for the admission of the teeth of spur-wheels, I cut notches in the edges E and E', (see drawings,) to permit an exposure at those points of the edges of the wick-holder plate A, as seen in figs. 4, 5, and 6. I make a wick-holder of a single plate of metal, (see A, fig. 1,) by turning its edges C and C' in such a manner as to allow a cotton-wick to be easily drawn into it, as seen in W, fig. 2, and so that it will pass with ease through the wick-tube B. I also at the lower end turn off a small lip, D, as a stop to prevent it from rising higher in the wick-tube than necessary, (see D, figs. 1 and 6.) On the axle F, I attach firmly, at a little less distance apart than the width of the plate A, two small wheels or friction-collars, of brass or other metal, with their inner sides or faces bevelled, as seen in G and G', fig. 6, so that they will clamp the edges of the plate A when pressed upon it by the action of the spring S and S', which I attach to the inside of the burner I in such a manner as to bear firmly with its prong or prongs upon the axle F, as may be seen in figs. 4, 5, and 6. In the sides of the burner, I cut the slots K and K' as bearings for the axle F, so as to allow it free play under the action of the spring S and S'. Now, by reference to the drawings, it will be seen, that when the plate A, charged with a wick, is inserted into the wick-tube B, its edges, through the notches E and E', where they are exposed, will be seized by the friction-collars G and G', and if the button H, on the end of the axle F, be

turned or twisted by the hand, the plate A will rise or lower with perfect ease and certainty, thus adjusting the upper end of the wick above the wick-tube B, to the amount or volume of flame required.

The advantages of my improvement are as follows: A wick can be inserted into the wick-tube with much greater facility than in that of lamps of common use. As there is no direct action of the moving power, on the body of the wick itself, it will continue to hold the shape in which it is trimmed without change, and thus give the largest and brightest flame which can be obtained from a lamp. It will give more freedom to the passage of oil through the wick; and a wick never being ravelled, as by the spur-wheels which enter it, as in ordinary lamps, will last until it is all consumed, for as soon as a wick, from the process of burning and trimming, becomes too short to take the oil from the fountain, the end of another wick may be added to it, and thus continue to pass the flow of oil unobstructed, as will be seen at N, fig. 2, it being only necessary, when the upper wick is pushed up in trimming, to push up the lower one again until it touches the first.

What I claim as new, and as of my invention, and for which I desire to obtain Letters Patent, is—

The single plate A, with the turned edges C and C', and the bent stop-piece D, in combination with the wick-tube B, the notches E and E', the bevelled friction-collars G and G', the axle F, the spring S and S', and the burner I, substantially as described, and for the purpose set forth.

I also claim the notches E and E', in the edges of the wick-tube B, substantially as described, and for the purpose set forth.

I also claim the bevelled friction-collars G and G', in combination with the axle F, the plate A, the wick-tube B, the spring S and S', the notches E and E', and the slots K and K', when arranged together and with regard to the adjustment of wicks in oil-burning lamps.

J. B. ALEXANDER.
